UNITED STATES PATENT OFFICE.

EMIL JAGENBERG, OF DUSSELDORF, GERMANY.

LABEL GUMMING AND ATTACHING MACHINE.

1,001,854.

Specification of Letters Patent. Patented Aug. 29, 1911.

Application filed October 19, 1910. Serial No. 587,817.

To all whom it may concern:

Be it known that I, EMIL JAGENBERG, a citizen of Germany, residing at Dusseldorf, Germany, have invented a new and Improved Label Gumming and Attaching Machine, of which the following is a specification.

This invention relates to a machine of novel construction for gumming labels and securing the gummed labels to suitable objects.

The machine is simple in construction, operates quickly, is accurate and thoroughly reliable in its movements.

15 In the accompanying drawing: Figure 1 is a side elevation of a machine embodying my invention; Fig. 2 a section through the drum, tongue and coöperating parts, and Fig. 3 a similar section showing the parts 20 in a different position.

Upon a rotating shaft *c* is mounted a drum *a* composed of a pair of spaced disks connected at their periphery by one or more segments *b*. The labels are stacked in a 25 magazine *d* pivoted to a slide *e*, which is guided on the machine frame tangentially to drum *a*, so that as the slide moves obliquely upward, the bottom label will impinge against segment *b*. Upon shaft *c* is 30 mounted a cam *f*, which engages a cam roller journaled in an arm *e'* of slide *e*. The contour of the cam is such that after the bottom label has engaged segment *b*, the speed of the further ascending slide is 35 equal to the speed of the segment. In this way the bottom label will adhere to the segment snugly and without wrinkles, the segment having been previously coated with an adhesive by rollers *g*. Upon the 40 further rotation of drum *a*, the bottom label will be drawn out of the magazine, while the superposed labels will be held against withdrawal by hooks formed at the mouth of the magazine, and against which they 45 are pressed by a follower *h*.

Upon the machine frame is guided a horizontally movable tongue *i* provided with a number of spaced relatively fixed jaws *k* adapted to engage transverse grooves *b'* of segment *b*, and spaced movable jaws *l*. At its rear end tongue *i* is connected to rod *m* pivoted to elbow lever *n* which engages a cam *o* fast on a countershaft *p* driven from shaft *c*. Movable jaws *l* are provided with an arm *q* having a roller which is spring held against the bottom of a horizontally

arranged vertically movable rail *r*. This rail is connected at one end to a pivoted arm *s* and at its other end to a pivoted elbow lever *t* which operatively engages the 60 cam *u*.

Tongue *i* is advanced by cam *o* when segment *b* occupies approximately its uppermost position, so that the lower jaws *k* will enter grooves *b'* to be located below the 65 forward end of the label adhering to said segment. Simultaneously therewith cam *u* will so swing lever *t*, that rail *r* is raised, to lower jaws *l* upon the label and thereby clamp it to jaws *k*. Jaws *k*, *l* are then 70 retracted by cam *o* with a speed equal to that of segment *b* so that the label is peeled off the same. The jaws finally attach the label to the object *v* which has been brought into the position illustrated in Fig. 1 im- 75 mediately after segment *b* has cleared support *v'* during its continued rotation. Cam *o* is so shaped that the jaws *k*, *l* come to a temporary standstill during the above label grasping and attaching operations, so as to 80 insure a reliable working of the machine.

The attachment is effected by a plunger, or by elevating the object against a suitable abutment. During the receding motion of the tongue, movable jaws *l* are opened to 85 liberate the label. Of course the tongues may be so placed as to coöperate with the segment when the latter arrives at its bottom or other position.

I claim:

1. In a label gumming and attaching machine, a continuously rotating segment, means for applying an adhesive thereto, means for applying a label to said segment, a clamping jaw movable in substantial tangentiality to said segment, means for advancing and collapsing the jaws to grasp the label, and means for retracting the jaws with a speed equal to that of the segment to peel the label off said segment and attach it to an article, the jaws being at a temporary standstill during said label grasping and attaching operations. 90

2. In a label gumming and attaching machine, a continuously rotating segment 105 having a grooved edge, means for applying an adhesive thereto, means for applying a label to said segment to partly overlap its grooves, clamping jaws movable in substantial tangentiality to said segment and 110 adapted to enter said grooves, means for advancing and collapsing the jaws to grasp

the overlapping label section, and means for retracting the jaws with a speed equal to that of the segment to peel the label off said segment and attach it to an article, the 5 jaws being at a temporary standstill during said label grasping and attaching operations.

3. In a label gumming and attaching machine, a continuously rotating segment, 10 means for applying an adhesive thereto, means for applying a label to said segment, a lower clamping jaw movable in substan-

tial tangentiality to said segment, means for oscillating said jaw, an upper jaw pivoted to the lower jaw and having a 15 spring-influenced arm carrying a roller, a rail arranged in parallelism with the path of the lower jaw and engaged by the roller, and means for raising and lowering said rail to close and open the jaws.

EMIL JAGENBERG.
